APPARATUS FOR CONDITIONING SOLES

Mieth Maeser and Helge Gulbrandsen, Beverly,
Mass., assignors to United Shoe Machinery Cor-
poration, Flemington, N. J., a corporation of
New Jersey

Application July 5, 1946, Serial No. 681,490

19 Claims. (Cl. 12—1)

1
This invention relates to apparatus for conditioning shoe parts, particularly soles, prior to attachment to shoes.

As illustrated by way of example, in a machine for treating at one time a plurality of soles with hot vapor laden air both to temper the soles and activate the cement thereon, the apparatus includes a cabinet containing a conditioning chamber with supports for soles, a source of warm vapor laden air and means for superheating the vapor laden air before it reaches the soles to insure that all of the moisture is in a gaseous form when the air reaches the soles. In accordance with one feature of the invention the superheater is arranged to form a long, tortuous path through which the vapor laden air must pass before reaching the conditioning chamber, the path being of such length that it is possible to exercise an extremely accurate control over the temperature and relative humidity of the tempering atmosphere when it reaches the conditioning chamber. This accurate control is highly necessary for the efficient activation of the different sole cements which may be activated in the chamber as those cements respond to different temperature conditions.

In machines of this type it is important to maintain an even temperature in all parts of the conditioning chamber so that all portions of the soles will be uniformly treated. It is also important in these machines, which are normally used in conjunction with other machines such as shoe presses, that the operator have ready access to the soles in the chamber each time the associated machine is operated in order to facilitate the loading of the press. In prior machines relatively large openings into the conditioning chamber are provided for the operator's convenience in inserting and removing shoe parts from the chamber. While these openings permit ready access to the soles in the chamber, it has been found that they also permit a draft of colder air to enter the chamber through the lower part of the opening under the stream of escaping hot air. The colder air disturbs the uniform atmospheric condition within the chamber with the result that it is difficult to give the same uniformity of treatment to the portion of the sole near the opening as is given to the remainder of the sole located further within the chamber.

2
where the temperature and humidity are substantially constant. This difficulty is largely overcome in applicants' machine where, in accordance with another feature of the invention, a plurality of restricted openings are provided in the casing leading to the supporting means for the soles together with closures for the openings and means for successively opening the closures so that at any given time there is only one restricted opening which leads into the portion of the chamber wherein it is desired to insert or remove a sole. This arrangement materially reduces the amount of cold air admitted to the chamber and restricts it to a location where it will least affect the uniform treatment of other soles within the chamber inasmuch as it leads to a portion of the sole support which is normally empty.

In accordance with another feature of our invention, trays for supporting the soles are arranged to slide through the restricted openings in the casing and means are provided for successively moving the trays from within the casing through the openings to a position where the sole is conveniently presented to the operator. As illustrated, the tray moving means comprises a treadle controlled mechanism which leaves both of the operator's hands free for other duties.

In the drawings,
30 Fig. 1 is a side elevation partly in section of a machine embodying the invention;

Fig. 2 is a rear elevation of a portion of the machine illustrating the sole ejecting mechanism;

35 Fig. 3 is a schematic view, partly in section, illustrating the air supply system, the view being taken from a point slightly above the apparatus;

Fig. 4 is a front view of the upper portion of the machine;

40 Fig. 5 is a plan view of a superheating unit with a portion of a cover plate removed to show the tortuous air passage; and

Fig. 6 is a vertical section of the superheating unit taken on the line VI—VI of Fig. 5.

45 The illustrated apparatus is embodied in a machine designed to stand on the floor and consists of a base 10 and a sole-treating cabinet 12 which is secured to the top of the base by screws 14. Hot vapor laden air is supplied to the cabinet 12 by a closed boiler 16 which is

mounted on a shelf 18 located in the lower portion of the base 10. The boiler 16 contains a body of water supplied through a pipe 20, the water being heated to a desired temperature by an immersion heater 22 (Fig. 3). The temperature of the water is controlled by a thermostatic bulb 24 which is connected through an appropriate connection 26 to a thermostat 28 (Fig. 4) mounted on the front portion of the base 10 just below the cabinet 12.

To accelerate the transfer of vapor from the water to the conditioning chamber, the tank is provided with means for bubbling compressed air through the water. This means consists of an air pump 30 (Fig. 1) which is driven by a motor 32 through the medium of a belt 34, the air pump and motor both being mounted on the shelf 18. Compressed air is led from the pump 30 through a pipe 35 to a filter 36 (Fig. 3) containing spun glass or other appropriate filtering material and thence through a pipe 38 to a manifold 40 located in the bottom of the tank, the compressed air escaping from the manifold through small perforations 42.

It is highly important that the temperature and relative humidity of the hot vapor laden air supplied to the sole treating chamber be closely and accurately controlled over a wide range of temperatures. This is due to the fact that different sole cements which are activated in the sole treating chamber respond to different temperature conditions. Also, when an excessive amount of moisture is present in the air fed into the chamber, the soles located therein are wetted to an undesirable degree which may cause discoloration that cannot be removed by a subsequent buffing operation.

In the illustrated machine the necessary fineness of control over the temperature and relative humidity of air reaching the conditioning chamber is obtained by inserting a superheating unit 46 (Figs. 3, 5 and 6) in the conductor circuit which leads the hot moist air from the boiler 16 to the conditioning chamber 12. This unit adds the necessary amount of heat to the air to bring it to the desired temperature and ensures that all of the moisture is vaporized. The superheating unit is connected with the boiler 16 by a pipe 44 (Fig. 3), and consists of a block 48 (Fig. 6) having long tortuous passages 50, 51 formed by grooves in its upper and lower surfaces. The passages 50, 51 are covered by upper and lower plates 52, 54 which are fastened to the block 48 by bolts 56. Hot moist air rising from the boiler passes through the pipe 44 to a nipple 58 (Fig. 5) connected to the lower passage 50 of the superheating unit and, after completely traversing the lower passage, is led to the upper passage through an opening 60 in the block. The air then passes back and forth through the upper passage 51 and flows through an opening 62 in the upper plate 54 and an apertured block 63 (Fig. 3) to a manifold 64 located just beneath the soles in the treating chamber, the manifold being provided with a number of small openings 66 which permit the air to escape into the chamber.

While flowing through the long tortuous passages 50, 51, additional heat is imparted to the hot moist air by a heating unit 68 (Fig. 5) which is embedded in the block 48 and is connected to an appropriate source of electricity by leads 70. The quantity of heat given off by the heating unit is controlled by a thermostatic unit 72 which is seated in the block 48 and is connected to a thermostat 74 located in the front of the base

10 alongside the water temperature controlling thermostat 28 (Fig. 4).

To assist in the initial heating of the sole treating chamber 12 and also in maintaining a uniform temperature therein, a heating unit 76 (Fig. 3) is located in the top of the chamber. This unit is connected to a convenient source of electricity by leads 78 and is provided with a thermostatic unit 80 which is connected to a thermostat 82 (Fig. 4) located alongside the thermostat 74.

Soles in the treating chamber 12 are supported on seven trays 84 which are arranged to slide in and out through openings 85 in the front of the chamber, the trays being successively ejected from the chamber a sufficient distance to present soles located thereon to the operator by mechanism that will now be described. Referring to Figs. 1 and 2, it will be seen that the rear end of each tray is connected by a rod 86 and a link 88 to a lever 90 which is pivoted on a shaft 91 and operated by an associated cam 92 mounted on a shaft 94. The seven cams 92 are equally spaced about the shaft 94 so that during one revolution of that shaft, each of the cams will act against the lower end of its associated lever thereby causing the lever to move inwardly and eject the tray to which it is connected. The lower ends of the levers are held in engagement with their associated cams by springs 96 which are connected at one end to a flange 98 depending from the top of the base 10 and at their other ends to pins 100 projecting out from the lower ends of the levers. Thus, when the high point of a cam 92 passes from beneath the end of its associated lever, the spring 96 will cause the lower end of the lever to follow the cam surface inwardly toward shaft 94 thereby moving the upper end of the lever away from the cabinet 12 and its connected tray or drawer back within the cabinet. At the same time this withdrawing action is taking place, the next cam in series is causing its associated lever to eject the next drawer from the cabinet.

The shaft 94 is rotated by a gear 102 fastened to its right end, as viewed in Fig. 2, which meshes with a driving pinion 104 (Fig. 1) mounted on a shaft 106. The ratio between the pinion 104 and gear 102 is 7:1 so that each time the pinion is rotated one revolution the gear 102 is rotated one-seventh of a revolution thereby causing the projecting drawer to be moved back within the cabinet and the next drawer in series to be ejected. The shaft 106 is driven by the motor 32 which is coupled by the belt 34 to reduction gearing (not shown) in a housing 108 and thence through a shaft 110 (Fig. 2) and clutch 112 to the shaft 106.

The clutch 112 is automatically disengaged at the completion of each revolution of the pinion 104 by controls which will now be described. The clutch 112 consists of a clutch member 114 fixed to the shaft 110 and a shiftable clutch member 116 slidably mounted on the shaft 106 (Fig. 2). The clutch member 116 is controlled by a shift fork 118 which is in turn operated by a lever 120 fastened to the shift fork. The clutch members are urged into engagement by a spring 122 which is connected at one end to the upper portion of the lever 120 and at its other end to the machine frame. The clutch members 114 and 116 are automatically disengaged after one revolution of the pinion 104 by a clutch throwout member 124 which has a hooked end 126 that engages behind the lower end of the lever 120 and is connected at 75 its other end to the lower end of a clutch throw-

out arm 128. The throwout arm 128 is pivoted on a pin 130 located above the shaft 106 and is provided near its midpoint with a roll 132 that rides behind a disk-like flange 134 fastened to the shaft 106. The face of the flange 134 engaged by the roll 132 has a highpoint 136 which, at the completion of each revolution, automatically forces the throwout arm 128 and member 124 to the right, as viewed in Fig. 2, thereby disengaging the clutch member 116. The roll 132 is held against the face of the flange 134 by a spring 138 and the throwout member 124 is urged in a heightwise direction by a spring 140 to cause the hooked end 126 to engage behind the arm 120.

The throwout member 124 is depressed so as to release the lever 120 and permit the spring 122 to cause engagement of the clutch members 114 and 116 by downward movement of a link 142 which has a hooked end 144 that engages over a projection 146 on the end of the member 124, the link 142 being operated by a treadle 148. After the arm 124 has been moved downward sufficiently to release the lever 120, a projection 150 on the link 142 will strike a roller 152 causing the link to move to the right against the influence of a spring 154 until the hook 144 has been moved out of engagement with the projection 146. At this point the spring 140 will cause the member 124 to rise until its hooked end 126 strikes the beveled lower end of the lever 120 and the spring 138 will cause the clutch throwout arm 128 and member 124 to move to the left as viewed in Fig. 2 until the roll 132 strikes the flange 134. As the flat portion of the flange lies opposite to the roll when this action takes place, the motion imparted to the member 124 will be sufficient to move its hooked end past the beveled lower end of the lever 120 when it will be pulled up by spring 140 into the position shown in Fig. 2. Thus when the pinion 104 completes its revolution and the arm 128 is again moved to the right by the highpoint 136 on the flange 134, the hooked end 126 of the member 124, which now engages behind the end of the lever 120, will impart a similar movement to that lever and cause the clutch member 116 to move out of engagement with the clutch member 114.

At such time as the operator releases the treadle 148, the treadle and rod 142 will move upwardly under the influence of a spring 156 (Fig. 1). As the rod 142 moves upwardly, its hooked end 144 will strike the projection 146 on the member 124 and will be shifted to the right until it passes the projection when it will be snapped back into overlying relation with the projection by the spring 154.

Each of the openings 85 in the cabinet 12 is provided with a pair of doors 158 (Fig. 4) which are pivoted on pins 160 and are biased to a closed position by springs 162. The doors are opened by outward movement of the trays 84, but as only one tray at a time is projected from the cabinet the remainder of the doors will be closed at all times. The single small opening provides the necessary draft through the cabinet and at the same time will permit only a small amount of colder air to enter the chamber. As this air enters the portion of the chamber normally occupied by the projecting tray it will not noticeably affect the atmospheric condition throughout the remainder of the chamber where soles are being treated.

Having thus described our invention, what we claim as new and desire to secure by Letters Patent of the United States is:

1. A conditioning apparatus comprising a cas-

ing, means for supporting shoe parts in the upper portion of said casing, means for supplying a continuous current of hot vapor laden air to the upper portion of said casing, a unit for superheating the hot vapor laden air before it reaches the portion of the casing containing the shoe part supporting means, said unit containing a long tortuous passage for the vapor laden air, means for heating said passage, and an additional heating unit in the top of the casing.

2. A conditioning apparatus comprising, means for supporting shoe parts inside the upper portion of the apparatus, a water container in the lower portion of the apparatus, means for heating the water, means for forcing air through the water in sufficient quantity to maintain a constant outward current of hot vapor laden air, a heated air conductor for superheating the air, said conductor being interposed between the water and the shoe part supporting means in the upper portion of the apparatus, and means in addition to said air conductor for heating the upper portion of the apparatus.

3. A conditioning apparatus for shoe parts comprising, a chamber having means for supporting shoe parts inside said chamber, a water container below said chamber, an immersion heater for said water, nozzles immersed in the water for emitting jets of air under pressure to increase the vapor output of the heated water so as to maintain a constant flow of hot vapor laden air, a long tortuous air conductor for leading the air arising from the water to the chamber, means for conducting the hot vapor laden air from the water container to said air conductor, means for heating the air conductor so as to remove excess moisture from the air, and additional means for heating the upper portion of the chamber to maintain a uniform temperature therein.

4. A conditioning apparatus having a restricted opening in its upper portion and arranged to contain a body of water in its lower portion, means for supporting shoe parts inside the upper portion of the apparatus, means for heating the water, means for forcing compressed air through the heated water, an air conditioning unit interposed between the surface of the water and the support for the shoe parts comprising a tortuous passage for said vapor laden air, means for heating the air conditioning unit thereby to superheat the air passing therethrough and ensure that the moisture content is in a pure gaseous form, and additional means for heating the upper portion of the apparatus.

5. A conditioning apparatus comprising a casing, means for supporting shoe parts within said casing, a plurality of restricted openings in said casing leading to the supporting means, closures for said openings, and closure operating means arranged to open said closures whereby when one closure is opened another will be closed so that only one restricted opening will be open at any time.

6. A conditioning apparatus comprising a casing, means for supporting shoe parts within said casing, a plurality of restricted openings in said casing leading to the supporting means, closures for said openings biased to a closed position, and power operated means for sequentially opening said closures in such a manner that when one closure is opened the preceding closure will be closed.

7. A sole conditioning apparatus comprising a casing, trays arranged to support soles within

said casing, power operated means for withdrawing the trays successively from within the casing to present the soles carried thereby to an operator, and resilient means for returning the trays into the casing.

8. A conditioning apparatus comprising a casing, trays arranged to support shoe parts within said casing, treadle controlled means for successively ejecting said trays from the casing sufficiently to present the shoe parts to an operator, and a spring for returning each tray into the casing as the next tray is ejected.

9. A conditioning apparatus comprising a casing, trays arranged to support shoe parts within said casing, and power operated means for successively moving said trays in and out of said casing to present shoe parts carried thereby to an operator, said means moving a tray into the casing each time it moves a tray out of said casing.

10. A conditioning apparatus comprising a casing, a restricted opening in said casing, a tray slideable through said opening and arranged to support shoe parts within said casing, and treadle controlled means for operating the tray, said treadle controlled means including a clutch and means operated by the clutch for sliding the tray back and forth through the opening with a dwell at the end of each sliding movement.

11. A conditioning apparatus comprising a casing, means for supplying hot vapor laden air to the casing, a plurality of restricted openings in said casing, closures normally restricting said openings, trays slideable through said openings and arranged to support shoe parts within said casing, and power operated means for successively withdrawing said trays from within the casing and also opening said closures to present the shoe parts carried thereby to an operator, said means being constructed and arranged to cause one closure to remain open at all times to permit the exit of vapor laden air from the casing.

12. A conditioning apparatus comprising a casing, a plurality of restricted openings in said casing, trays inside the casing slideable through said openings and arranged to support shoe parts within the casing, power operated means for moving the trays back and forth through said openings, and treadle controlled means for said power operated means.

13. A conditioning apparatus comprising a casing, a plurality of restricted openings in said casing, trays slideable through said openings and arranged to support shoe parts within the casing, power operated means including a clutch for moving said trays back and forth through the openings, said clutch being automatically disengageable, and treadle controlled means for engaging said clutch.

14. A conditioning apparatus comprising a casing, a plurality of restricted openings in said casing, trays slideable through said openings and arranged to support shoe parts within said casing, closures for said openings arranged automatically to close the openings when the associated tray is positioned within said casing whereby only the closure associated with the withdrawn tray will be open at any given time, and means for sliding said trays successively through said openings, said means withdrawing the preceding tray as it slides the next tray through its opening.

15. A sole conditioning apparatus comprising a casing, a plurality of restricted openings in said casing, trays slideable through said openings and

arranged to support shoe soles within said casing, means for supplying hot vapor laden air to the tray portion of said casing for treating the shoe soles, closures for said openings each being arranged automatically to close when its associated tray is positioned within said casing thereby facilitating the maintenance of a uniform atmospheric condition within the casing, and means for sliding the trays successively back and forth through the openings so that the closure of only one opening will be open at any one time, the open closure allowing exit of vapor laden air from the casing to cause circulation of said air therein.

15. A conditioning apparatus comprising a casing, means for supporting shoe parts within the casing, a plurality of restricted openings in said casing leading to the supporting means, closures for said openings, a water container communicating with the casing, means for heating the water, means for forcing air through the water in sufficient quantity to supply a continuous current of hot vapor laden air to the casing, a closed heated air conductor for superheating the air before it reaches the portion of the casing containing the shoe part supporting means, and power operated means for successively opening said closures whereby only one restricted opening will be open at any one time.

16. A conditioning apparatus comprising a casing, trays arranged to support shoe parts within said casing, a water container communicating with the casing, means for heating the water, means for forcing compressed air through the heated water to increase its vapor output and maintain a constant flow of hot vapor laden air to the casing, a unit for superheating the hot vapor laden air before it reaches the portion of the casing containing the trays, and treadle controlled means for successively ejecting said trays from within the casing sufficiently to present the shoe parts carried thereby to an operator.

17. A conditioning apparatus comprising a casing, a plurality of restricted openings in said casing, trays slideable through said openings and arranged to support shoe parts within said casing, a water container in the lower portion of the apparatus communicating with said casing, means for heating said water, means for forcing air through the heated water to produce a constant current of hot vapor laden air to the casing, power operated means for successively withdrawing said trays from within the casing sufficiently to present the shoe parts carried thereby to an operator, said power-operated means being arranged to return each tray into the casing as the next tray is withdrawn so that only one tray will be withdrawn at any one time, and treadle controlled means for actuating said power operated means.

18. A conditioning apparatus comprising a casing, a plurality of restricted openings in said casing, trays slideable through said openings and arranged to support shoe parts within said casing, a water container in the lower portion of the apparatus communicating with said casing, an immersion heater for heating said water, means for forcing air through the heated water to produce a constant current of hot vapor laden air to the casing, a heated air conductor for superheating the air, said conductor including a long tortuous passage interposed between the water and the trays in said casing, power operated means for successively withdrawing said trays from within the casing sufficiently to present the

shoe parts carried thereby to an operator, said power operated means being arranged to return each tray into the casing before the next tray is withdrawn so that only one tray will be withdrawn at any one time, and treadle controlled means for actuating said power operated means.
